UNITED STATES PATENT OFFICE.

GEORGE F. TAFT, OF BOSTON, MASSACHUSETTS.

SHIELD FOR AUTOMOBILE HEADLIGHTS.

Application filed January 31, 1921. Serial No. 441,118.

To all whom it may concern:

Be it known that I, GEORGE F. TAFT, a citizen of the United States, residing at Boston, in the county of Suffolk and State of Massachusetts, have invented new and useful Improvements in Shields for Automobile Headlights, of which the following is a specification.

This invention relates to shields for vehicle headlights and has for its object to provide a device which may be attached to a headlight for the purpose of confining the rays of light which are projected horizontally by said headlight to a limited area in advance of said vehicle and at a predetermined height above the ground, a portion of the rays of light from said headlight being reflected by said shield downwardly upon the roadway directly in front of the vehicle and other of said rays being reflected laterally toward the right and left, all of said rays of light being so reflected that no direct glare from the source of illumination will be directed into the eyes of operators of approaching automobiles.

The invention consists in the combination and arrangement of parts set forth in the following specification and particularly pointed out in the claims thereof.

Referring to the drawings:

Figure 1 is a central vertical section through a headlight having a shield embodying my invention attached thereto.

Fig. 2 is a front elevation of the shield.

Fig. 3 is a side elevation of the shield.

Fig. 4 is a top plan view of the shield.

Fig. 5 is a central vertical section through a headlight, a shield representing a modified embodiment of my invention being attached thereto.

Fig. 6 is a front elevation of the shield illustrated in Fig. 5.

Fig. 7 is a side elevation of the shield as viewed from the right of Fig. 6.

Fig. 8 is a horizontal section taken on the line 8—8 of Fig. 6.

Like numerals refer to like parts throughout the several views of the drawings.

In the drawings, referring particularly to Figures 1 to 4 inclusive, 10 represents a headlight of any desired construction in which 11 is the source of illumination, preferably an electric light bulb, 12 a parabolic reflecting surface and 13 the lens which is held in position upon the headlight by a band 14 of the usual well known construc-

tion. Also fast to the front of the headlight 10 by the band 14 is a shield 15, preferably constructed of sheet metal, said shield being held against the front surface 60 of said lens by said band. The shield 15 comprises a circular rim 16 to which a visor 17 is attached, said visor in a vertical plane being disposed at an angle to said rim 16 and lens 13 and in a horizontal plane curving outwardly from said rim. The visor 17 has a reflecting surface 18 upon the rear side thereof against which rays of light from the electric light bulb 11 and the parabolic reflecting surface 12 may strike and be reflected downwardly at different angles to illuminate the roadway directly in front of the vehicle upon which the headlight may be mounted. The visor 17 has a lower edge 19 so located that the parallel horizontal rays of light from the parabolic reflecting surface 12 may pass therebeneath to provide sufficient illumination in advance of the vehicle and at a given distance above the ground to meet the various traffic requirements and regulations.

The visor 17 has a pair of openings 20 provided therein and projecting outwardly from the outer surface of said visor adjacent to a portion of the edge of each of said openings are vanes 21. The vanes 21 are provided with a reflecting surface 22 upon their rear sides against which rays of light from the electric light bulb 11 and the parabolic reflecting surface 12 passing through 90 the openings 20 may strike and be reflected laterally at different angles to illuminate the roadway to a limited extent upon each side of the vehicle.

In its operation the visor 17 of the shield will allow a certain volume of parallel rays of light from the parabolic reflecting surface 12 to be projected forwardly in advance of the vehicle, while the rays of light striking the reflecting surface 18 of said visor will all be reflected downwardly upon the ground directly in advance of the vehicle. The rays of light which pass through the openings 20, however, will strike the reflecting surface 22 of the vanes 21 and will be reflected laterally to the right and left at an angle to illuminate the roadway for a limited area at each side of the vehicle. The visor 17 and the vanes 21 are so positioned that they will obscure the direct glow from the headlight and at the same time will reflect the rays of light from

said headlight to meet the various traffic requirements and regulations.

In Figures 5 to 8 inclusive is illustrated a modified embodiment of my invention in which a shield 25 comprises a circular rim 26 to which the opposite ends of the main portion of a visor 27 are attached. An upper edge 28 of the main portion of the visor 27 is located approximately at the horizontal center line of the rim 26 and said main portion projects downwardly and forwardly, the lower edge 29 thereof being so located that parallel horizontal rays of light from the parabolic reflecting surface 12 may pass therebeneath to provide sufficient illumination in advance of the vehicle and at a given distance above the ground to meet the various traffic requirements and regulations. The main portion of the visor 27 has a reflecting surface 30 upon the under side thereof against which rays of light from the electric light bulb 11 and the parabolic reflecting surface 12 may strike and be reflected downwardly at different angles to illuminate the roadway directly in front of the vehicle upon which the headlight may be mounted.

Extending upwardly from the main portion of the visor 27 adjacent to the rim 26 are flanges 31 which project forwardly and inwardly a short distance from said rim and in effect form a part of the visor 27, said flanges being fastened to the rim 26 at practically the same angle as the portion of the visor 17 which is adjacent to the rim 16.

A pair of vanes 32 are mounted upon the main portion of the visor 27 projecting upwardly therefrom and being attached at their upper ends to the rim 26. Adjacent inner edges 33 of the vanes 32 meet in a vertically disposed straight line at a point adjacent to the lens 13. The vanes 32 extend forwardly and outwardly from where their edges 33 unite and the outer edges 34 thereof overlap the edges 35 of the flanges 31. The vanes 32 are provided upon their rear sides with a reflecting surface 36 against which rays of light from the electric light bulb 11 and the parabolic reflecting surface 12 may strike and be reflected laterally at different angles to illuminate the roadway upon each side of the vehicle. Openings 37 between the edges 35 of the flanges 31 and the vanes 32 in effect correspond to the openings 20 in the visor 17 previously described and perform the same functions. A shield constructed as illustrated in Figures 5 to 8 inclusive will reflect rays of light in a similar manner to the shield illustrated in Figures 1 to 4 inclusive, although the vanes 32, if constructed in the proportions illus-

trated, will reflect a greater volume of rays of light than will be reflected by the vanes 21. It is evident that the main portion 65 of the visor 27 may be attached to the rim 26 at any desired height thereon and the position of said visor upon said rim will determine the size of the vanes 32.

The shields as illustrated are constructed 70 to be attached to headlights which have been installed upon vehicles. It is evident, however, that if it is so desired, shields may be moulded in one piece of glass, being formed integral with the lens, the visor and 75 vanes being constructed sufficiently thick to provide the strength required. In the event of the shield being so constructed of glass, the outer surfaces of the visors and vanes are coated with any suitable substance to 80 provide the required reflecting surfaces therebehind. It is evident that this form of shield falls within the scope of the appended claims.

I claim:

1. A shield for headlights embodying therein a rim, a visor attached to said rim and adapted to be located in front of the lens of said headlight to limit the height and volume of the rays of light projected forwardly by said headlight, said visor having a surface adapted to reflect rays of light downwardly and also being provided with openings extending therethrough and a pair of vanes located adjacent to the edges of 95 said openings and projecting forwardly and outwardly from said visor and having surfaces adapted to project the rays of light which pass through said openings laterally from said headlight in both an upward and 100 downward direction.

2. A shield for headlights embodying therein a visor adapted to be located in front of the lens of said headlight to limit the height of the rays of light projected forwardly by said headlight, said visor having a surface adapted to reflect rays of light downwardly and also being provided with openings extending therethrough and a pair of vanes projecting forwardly and outwardly from said visor, the adjacent inner edges of said vanes meeting in a vertically disposed straight line adjacent to said lens, said vanes having surfaces adapted to reflect rays of light passing through said 110 openings laterally from said headlight.

In testimony whereof I have hereunto set my hand in presence of two subscribing witnesses.

GEORGE F. TAFT.
